PORTABLE PUNCHING TOOL

Arthur Marcoux, Hermosa Beach, Calif., assignor to
Douglas Aircraft Company, Inc., Santa Monica, California

Application May 19, 1953, Serial No. 356,011

3 Claims. (Cl. 164—94)

This invention relates to a device for piercing holes in light gauge metals, and more particularly to a portable punching tool for piercing holes in aircraft components to permit the easy attachment of anchor nuts, nut plates, or the like.

Heretofore, when it was found necessary to install a large quantity of nut plates or the like in a given structure, every attempt was made to complete the installation at the bench, where, by the use of old and well known drill-jig methods, the bolt hole and the nut plate rivet holes were drilled, the nut plates were riveted in position, and then the part was installed in its parent structure, e. g. an airplane fuselage or wing. If the structural part could not be fabricated at the bench, it was then necessary to install it in the parent structure, individually drill, with a hand-held electric drill, both the bolt holes and the nut-plate rivet holes, and then set the nut-plate rivets with a conventional rivet gun. This is obviously a time consuming, cumbersome, and generally unsatisfactory procedure. The nut plate holes are frequently not located properly with respect to the bolt holes, requiring re-drilling and re-location, if possible, or perhaps rejection of an expensive part, if correction is not possible.

The present invention comprises a vibratory or "rattle" type pneumatic hammer having a two-stage control or throttle, and an elongate J-shaped yoke attached thereto and adapted to receive a cooperating pair of male and female punching dies. The male die assembly has an elongate pilot pin which is inserted in a pre-formed pilot or bolt hole in the part and which insures that the punched holes will be located with respect to the bolt hole with positive dimensional accuracy. The tool is light, compact, and easily handled by both male and female operators, and obviates the difficulties heretofore enumerated.

In operation, the punching tool is disposed substantially perpendicularly to the plane of the sheet in which the holes are to be punched, and the throttle of the pneumatic hammer is depressed to its first stage, enabling the operator to slowly and controllably advance the pilot pin into the pre-drilled or pre-punched bolt hole. After the pilot pin is inserted, the throttle or control is depressed to the second stage, causing the hammer to "rattle," and forcing the male punching dies through the sheet to be pierced. The resulting holes are, of course, perfectly aligned with the pilot or bolt hole and subsequent assembly of the component is easily and readily accomplished.

One of the more important features of this invention is the use, in the combination, of the vibratory or "rattle" type pneumatic hammer for the punching operation. This type of hammer renders a series of rapid, moderately heavy, blows instead of the one extremely heavy "squeeze" utilized by the standard bench-type hammers. The use of the vibratory action instead of the conventional "squeeze" obviates the necessity for a heavy, cumbersome ram required by a "squeezer," and makes for a heretofore unachieved lightness and compactness. In addition, the series of moderate blows results in dimensionally accurate, crack-free holes, whereas the previously

2

used bench-type, single-stroke "squeezers" frequently resulted in skin crack around the edges of the holes, a condition that cannot be tolerated, particularly in aircraft work. The absence of peripheral cracks is attributable to the fact that each moderately heavy blow, while sufficiently forceful to enable a series of them to accomplish piercing, is not so powerful as to cause bending, and subsequent cracking, at the hole periphery at the outset of the operation, as is the case in the "squeeze" technique. The ultimate strength of the metal is exceeded only in the hole area and not in the parent sheet itself. With the ever-increasing use of such relatively brittle materials as titanium, the ability to produce crack-free holes simply and easily is extremely important.

The presently preferred form of this invention is illustrated in the accompanying drawings in which:

Figure 1 is a side elevational view of the tool with the components shown in section;

Figure 2 is a plan view of the tool with the valve mechanism shown in section;

Figure 3 is an enlarged fragmentary view of the male and female punch dies in position to punch the sheets, with the assemblies shown in section.

As illustrated in Figure 1, the tool, such as the Ingersoll-Rand model AR-12 as shown in Ingersoll Rand catalog 5606, 4th edition, 1949, comprises a standard, vibratory or "rattle" type of pneumatic hammer 12, having a body member 13, the body member having a mounting lug 14 adapted to receive a yoke or frame member on the lower portion thereof. Within the body member 13 of the hammer is located a first piston assembly 15 comprising a head block 17 adapted to slide or reciprocate within the body member, a hollow, elongate, spring biased barrel or piston 18 threadedly engaged with head block 17, and having within its bore 19 a second piston or "slug" 20 adapted to be rapidly reciprocated in the bore by the air stream, and a spring-biased force transmitting member 22 disposed in the end of the barrel 18 in axial alignment with piston 20 and adapted to receive and transmit the percussive forces of piston 20. In the uppermost end of body member 13 is a plunger member 23 slidably disposed in the body member and adapted to engage head block 17 in face-wise contact. Suitable valve means 24 for metering the incoming air to both the rear face of plunger member 23 and to the second piston or slug 20, and controlled by control handle 25, permits the operator in a well known manner to actuate either the first piston assembly 15 or the second piston 20, at his discretion.

Attached to body member 13 at mounting lug 14 is an elongate, substantially J-shaped, frame or yoke member 26, having semi-permanently affixed female punching die assembly 27 at the lower end thereof. In this embodiment of the invention, the female punching die assembly 27 comprises two cylindrical sleeves 28 having hardened peripheral bosses 29 thereon, each of the sleeves 28 being adapted to receive in sliding contact a male punching die. Located between the holes 28 is an elongate, cylindrical pilot hole 30 which is adapted to slidably engage with a pilot pin in a male die assembly and guide the pilot pin and die assembly in its proper path.

Fastened to yoke member 26 at about its midpoint, is a die assembly receiving member 32, having a substantially U-shaped slot or cut in one end adapted to receive and guide a reciprocatable male punching die assembly 33 therein, and having a detachable cover plate 34 closing the open end of the "U" to retain the die assembly in position. Slightly to the right (as shown in Figure 1) of the U-shaped cut is located a cylindrical spring retaining or well 35, having a coil spring 37 therein, the spring being adapted to engage with a spring receiving stud 38 located on the male die assembly so as to urge the assembly to its uppermost position at all times.

The male punching die assembly 33 is slidably disposed in receiving member 32 and its upper face 39 engages force transmitting member 22 in facewise contact at all times. It comprises a solid, rectangular die holding block 40, having two standard male punching dies 41 disposed against stop shoulders 42 in die wells 43, each of the dies being locked in position by a spring loaded ball 44 which enters the block through channel 45 and engages with an annular groove 47 located in the mid-portion of the dies. To remove the dies, it is only necessary to unload the ball-biasing spring 48 slightly, permitting ball 44 to withdraw slightly upward in channel 45, and the dies 41 will drop out of the assembly. New dies are inserted by pushing them into the die wells 43 until they bottom on stop shoulder 42, then replacing spring 48 and ball 44 in the locking position. A round, elongate pilot pin 49 having a frusto-conical point 50 thereon is located in well 52 and is biased by spring 53, backed up by threaded plug 55. The pilot pin 49 is substantially longer than the punching dies 41, and point 50 always protrudes through the rubber stripper block 54 which encases the lower ends of the male dies, thus permitting the tool operator to readily insert the pilot pin in the preformed hole. While normal practice is to use a pilot pin which is about equal in diameter to the nut plate bolt hole, the pilot pin then penetrating fully through the preformed bolt hole in the sheet and engaging with the pilot hole in the female die assembly, in some instances, however, it is not necessary to do this. If a bolt hole is smaller than the pilot pin, the operator need only insert the frusto-conical tip 50 of the pilot pin in the smaller hole where it will come to rest and act as a centering member for the punches, the resilient mounting 53 of the pin permitting it to retract into the die block without damage.

In operation, the device is placed so that its longitudinal axis is substantially perpendicular to the plane of the sheet in which the holes are to be pierced. The operator depresses control handle 25 to its first stage or detent, causing valve 24 to admit metered air to the back (or upper as shown) side of plunger member 23, said plunger member 23 in turn forcing the entire first piston assembly 15 slowly and controllably downward, permitting the operator to insert pilot pin 49 in the preformed hole in the sheet. After the operator has inserted the pilot pin 49 in the hole so that stripper block 54 is snugly against the top of the sheet and the bosses 29 of female die 27 are firmly engaged against the lower side of the sheet, he depresses control handle 25 to the second stage, causing the valve 24 to direct additional air to actuate second piston or slug 20 while retaining the first piston assembly 15 in its lowered position. Slug 20 reciprocates rapidly, and "hammers" force transmitting member 22 which, being in facewise contact with male die assembly 33, causes the dies 41 in the assembly to apply a rapid series of punching forces to the sheets and ultimately force their way therethrough. The pilot pin 49, being in position in the pre-formed hole at all times during the piercing operation, insures that perfect alignment of the rivet holes and bolt hole is achieved.

After piercing is accomplished, the first piston assembly 15 is withdrawn upwardly away from the sheet, permitting the male die assembly 33 to be also urged upwardly by the action of spring 37 against stud 38, thereby withdrawing the punching dies 41 from the completed holes and returning the unit to its original position.

Different hole sizes are easily accommodated by simply removing cover plate 34 and the die assembly 33, and replacing the die assembly with one having the desired size punching dies. The pilot pin may also be readily interchanged in this manner. Worn or damaged pilot pins may be replaced by removing pilot pin spring 53 and withdrawing the pilot pin from pilot pin well 52, and inserting a new pin.

While the disclosed embodiment shows the male punching dies and the pilot pin to be parallel and also coplanar, it is obvious that, without departing from the spirit of the invention, the spacial relationship between the dies 5 and the pilot pin can be otherwise arranged. For example, for use in punching holes for so-called "corner" anchor nuts or nut plates, the dies and the pilot pin would be parallel, but disposed spacially at the vertices of a triangle. For "one lug" anchor nuts or nut plates, only one die need be used, or two dies both on the same side of the pilot pin.

While the presently preferred form of the invention has been illustrated and described herein, it will be appreciated that various changes may be made in the construction and arrangement of the parts without departing from the spirit of the invention, and it is intended that all such changes shall be embraced within the scope of the following claims.

I claim:

20. 1. A portable punching tool comprising: a pneumatic hammer, said hammer comprising first piston means adapted to controllably advance a reciprocatable punching die means, second piston means located within said first piston means, said second piston means being adapted to 25 deliver rapid percussions, a force transmitting member disposed in one end of said first piston means so as to receive the rapid percussions of said second piston means and transmit them to the reciprocatable punching die means, and control means arranged to provide independent control of the first and second piston means; frame means attached to said pneumatic hammer for supporting a reciprocatable die means; male punching die means, including a pilot pin, disposed in said frame means and arranged to be controllably advanced by said first piston means to a preselected position whereat the pilot pin will pass through a preformed opening in a workpiece and to receive intermittent blows from said second piston means when the preselected position is attained to punch the workpiece at points about the preformed opening; and 30 female punching die means located in said frame means and disposed in coaxing alignment with said male punching die means.

2. A portable punching tool, comprising: a yoke having opposite ends and an intermediate bight; a pneumatic hammer mounted on one of said ends and including a piston movable toward the other of said ends; an impact member on the piston selectively actuatable after said piston has moved toward said other end, the impact member being adapted to impart repeated blows to a punch; a 45 female die on the other of the yoke ends and having a pilot hole therein; a member attached to and extending from the bight of the yoke and having a channel-like guideway for supporting a die block therein; a die block mounted in the guideway for reciprocation toward and away from said female die, said block having a guide pin and a male punch mounted therein, each said punch and pin having an end thereof projecting out of said block for respective cooperation with the pilot hole and female die the movement of the piston effecting motion of the guide pin 50 through a preformed opening in a workpiece and the subsequent actuation of the impact member causing the male punch to form an opening in the workpiece proximate the preformed opening; a compressible stripper surrounding said projecting ends; resilient means normally urging said block away from the female die; and a removable cover plate maintaining the block within the guideway whereby, upon removal of the plate, the block may be moved laterally of the yoke ends for quick assembly and disassembly.

70. 3. In a portable punching tool, a sequential two-stage controllable pneumatic hammer including an impact member; a yoke member having two ends and an intermediate portion, said hammer being affixed to one of said ends; a female die having a pilot pin hole therein and being 75 mounted on the other of said yoke ends; a bracket with

a slideway therein extending from the intermediate portion of the yoke with the slideway in alignment with the impact member and female die; a male punch assembly mounted for reciprocation in said slideway, said assembly including a slide block with bores therein; a punch in one of said bores adapted to cooperate with the female die; a pilot pin resiliently mounted in another of said bores, said pin being receivable through a preformed opening in material being punched into the pilot pin hole in the female die; resilient stripper means surrounding the punch and pilot pin; said hammer in its first stage being adapted to advance the punch assembly toward the female die to grip material being punched between the stripper means and female die and to advance the pilot pin into the preformed opening, and in its second stage to impart an impact to the punch to form an opening in the material gripped, the resilient mounting of said pilot pin allowing the pin to be forced back into the block in the event of misalignment with the aforesaid preformed opening.
